Inventor:

WILLIAM R. UHLEMANN,

By *Robert Burns*,

Attorney

UNITED STATES PATENT OFFICE.

WILLIAM R. UHLEMANN, OF CHICAGO, ILLINOIS.

LENS-MOUNT.

1,290,420.

Specification of Letters Patent.

Patented Jan. 7, 1919.

Application filed March 28, 1918. Serial No. 225,144.

To all whom it may concern:

Be it known that I, WILLIAM R. UHLEMANN, a citizen of the United States of America, and a resident of Chicago, in the 5 county of Cook, State of Illinois, have invented certain new and useful Improvements in Lens-Mounts, of which the following is a specification.

This invention relates to means for attaching the rimless lenses of eyeglasses and the like to the intermediate clip members on the ends of the connecting bridge or other usual part of the article, and has for its object:

15 To provide a simple and efficient structural formation and association of parts wherein an effective locking of a lens to its carrying clip is effected in a ready and substantial manner, with the entire absence of 20 the usual screw fastenings, and with which ready detachment can be effected when so required, all as will hereinafter more fully appear.

In the accompanying drawing:—

25 Figure 1, is a detail side elevation illustrating the present invention applied to a portion of a lens and lens mount.

Fig. 2, is a detail section on line X²—X², Fig. 1, illustrating the preferred form of 30 the present invention.

Fig. 3 is a similar view of a modified form of the invention.

Like reference numerals indicate like parts in the different views.

35 Referring to the drawing, 1 designates a portion of an eyeglass lens, 2 a portion of the nose bridge or like parts of a mounting, and 3 the intermediate clip or yoke, fixedly attached to an end of the bridge 2, with its 40 jaws adapted to embrace the lens 1, as usual in eyeglass mountings.

In the preferred form of the present invention, as shown in Fig. 1 the clip or yoke 3 aforesaid is provided with a resilient 45 tongue 4 adapted for bearing against the edge of the lens 1, to permit limited rocking movement of said lens under accidental stresses, as set forth in detail in my prior Patent No. 933,502, dated September 7th, 50 1909. In the present structure the resilient tongue 4 serves the further purpose of maintaining the fastening of the structure in close and accurate engagement.

In the structure illustrated in Figs. 1 and 55 2, the side members or jaws of the aforesaid clip or yoke 3 are of a counterpart forma-

tion, and each jaw or member is formed with a slot 5 extending from near its base to its free end, and providing a receiving and guiding space for the resilient tongue 60 now to be described.

6 designates the resilient locking tongue or finger above referred to, arranged in the slot 5 aforesaid, and fixedly secured at one end, to the end wall of the slot 5 next adjacent to the base of the clip or yoke 3, and preferably in an integral manner as shown. The other end of the tongue or finger 6 is free, and is provided with an inclined dog or detent 7 adapted to engage in the usual 65 hole or orifice 8 adjacent to the margin of the lens 1 as shown, to lock the said lens in place in the clip or yoke 3. In such locked association of the parts, the resilient tongue 4 above described acts to yieldingly hold the 70 parts in properly engaged condition.

9 designates an eye formation on the tongue or finger 6, adjacent to the dog or detent 7, and adapted to receive a tapering pin or the like, in the operation of withdrawing the detent 7 from its engagement in the orifice 8 when it is desired to detach the lens 1 for repair or replacement.

90 In the modified structure illustrated in Fig. 3, only one jaw or member of the clip or yoke 3 is formed in the manner above described, the companion and opposed jaw or member having a solid formation, which at the judgment of the constructor, may have a fixed barb or detent 10 for engagement in the end portion of the orifice 8, opposite to the end portion of such orifice with which the resiliently carried detent 7 has engagement. When the barb or detent 10 95 as aforesaid, is employed, allowance will be provided between the clip jaws or members 100 to permit of lateral movement of the lens 1 in sliding into locking engagement with said barb or detent 10.

100 In the operation of effecting an engagement of the present construction the lens 1 is forced between the jaws of the clip 3, and in its passage between said jaws forces the resilient tongues 6 apart until the lens orifice 8 comes into alignment with the detents 7, when the same will move into the required locking engagement of the parts.

Having thus fully described my said invention, what I claim as new and desire to 105 secure by Letters Patent, is:—

110 1. In a lens mount, a yoke shape lens clip, a side member of which is formed with a

- slot, and a finger resiliently associated with said clip and arranged in said slot, and a locking detent carried by said finger and adapted for locking engagement in an orifice 5 of the lens, substantially as set forth.
2. In a lens mount, a yoke shape lens clip, and a finger resiliently associated with said clip and having a locking detent adapted for a locking engagement in an orifice of a 10 lens and an operating eye in adjacent relation to said detent, substantially as set forth.
3. In a lens mount, a yoke shape lens clip, one jaw of which is formed with a slot and a resiliently actuated finger arranged in said 15 slot and having a locking detent adapted for locking engagement in an orifice of a lens, substantially as set forth.
4. In a lens mount, a yoke shape lens clip, one jaw of which is formed with a slot and 20 a resiliently actuated finger arranged in said slot and having a locking detent adapted for locking engagement in a locking orifice of a lens and an operating eye in adjacent 25 relation to said detent, substantially as set forth.
5. In a lens mount, a yoke shape lens clip the side members of which are formed with slots, and opposed fingers resiliently associated with the opposed jaws of said clip 30 and arranged in said slots and locking detents adapted for engagement in an orifice of a lens, substantially as set forth.
6. In a lens mount, a yoke shape lens clip, and opposed fingers resiliently associated 35 with the opposed jaws of said clip and having locking detents adapted for engagement in an orifice of a lens and operating eyes in adjacent relation to said detents, substantially as set forth.
- 40 7. In a lens mount, a yoke shape clip the jaws of which are formed with slots, and opposed resiliently actuated fingers arranged in said slots and having locking detents adapted for locking engagements in an ori- 45 fice of a lens, substantially as set forth.
8. In a lens mount, a yoke shape clip the jaws of which are formed with slots, and opposed resiliently actuated fingers arranged in said slots and having locking detents adapted for locking engagement in an 50 orifice of a lens and operating eyes in adjacent relation to said detents, substantially as set forth.
9. In a lens mount, a yoke shape lens clip, a resilient finger carried by said clip and 55 adapted for bearing engagement against the edge of a lens, and a finger resiliently associated with said clip and having a locking detent adapted for locking engagement in an orifice of a lens, substantially as set forth. 60
10. In a lens mount, a yoke shape lens clip a resilient finger carried by said clip and adapted for bearing engagement against the edge of a lens, and a finger resiliently 65 associated with said clip and having a locking detent adapted for locking engagement in an orifice of a lens and an operating eye in adjacent relation to said detent, substantially as set forth.
11. In a lens mount, a yoke shape clip, a 70 resilient finger carried by said clip and adapted for bearing engagements against the edge of a lens, and opposed fingers resiliently 75 associated with the opposed jaws of said clip and having locking detents adapted for engagement in an orifice of a lens, substantially as set forth.
12. In a lens mount, a yoke shape clip, a resilient finger carried by said clip and adapted for bearing engagement against the 80 edge of a lens, and opposed fingers resiliently associated with the opposed jaws of said clip and having locking detents adapted for engagement in an orifice of a lens and operating eyes in adjacent relation to said de- 85 tents, substantially as set forth.

Signed at Chicago, Illinois, this 23rd day of March, 1918.

WILLIAM R. UHLEMANN.
